UNITED STATES PATENT OFFICE.

FREDERICK JAMES WEST, OF WINNIPEG, MANITOBA, CANADA.

AIR MIXER.

Application filed July 5, 1923. Serial No. 649,761.

To all whom it may concern:

Be it known that I, FREDERICK JAMES WEST, a subject of the King of Great Britain, and resident of the city of Winnipeg, in the Province of Manitoba, Canada, have invented certain new and useful Improvements in Air Mixers, of which the following is the specification.

The invention relates to improvements in air mixers particularly as utilized on internal combustion engines, such as automobile engines and an object of the invention is to provide a simple and durable device which can be readily installed on the engine and which will supply air to the intake manifold to mix with the firing mixture coming from the carburetor.

A further object is to construct the device such that the amount of air is automatically governed by the running condition of the engine and such that either hot or cold air will be admitted to the manifold, depending on temperature conditions of the engine, such latter being accomplished by a thermostatic control.

With the above more important objects in view the invention consists essentially in the arrangement and construction of parts hereinafter more particularly described and later pointed out in the appended claims, reference being had to the accompanying drawing in which:

Fig. 1 is a side view of an automobile engine equipped with my invention.

Fig. 2 is an enlarged detailed vertical sectional view through the air admission valves and parts associated therewith.

Fig. 3 is an enlarged detailed vertical sectional view through the controlling valve associated with the manifold.

Fig. 4 is a perspective view of the barrel of the controlling valve.

In the drawing like characters of reference indicate corresponding parts in the several figures.

The automobile engine 1 is of the customary internal combustion type and presents the usual intake manifold 2, exhaust manifold 3 and carburetor 4, which latter proportions and admits the firing mixture to the intake manifold. The customary throttle valve 5 is located in the intake manifold to control the amount of firing mixture passing up the intake manifold and this valve is supplied with the usual lever 6

which is operated by the throttle valve rod 7, the rear end of which is connected to a suitable crank 8. Usually the crank is controlled from the throttle lever (not shown) positioned on the upper end of the steering post 9.

All the above parts are of ordinary construction and on this account a further description of the same is not considered necessary.

An engine equipped with my invention is provided with the following parts:

A heating pipe 10 is passed through the exhaust manifold, one end of the pipe forming an exterior valve seat 11 and the other end being projected a short distance beyond the manifold and being fitted with a lateral screw threaded outlet nipple 12 which communicates with an air pipe 13 connected to the nipple by a screw coupling 14. A temperature controlled valve 15 is adapted to engage the seat 11. This valve in the present instance is of a cone shape and is carried by two bars suitably riveted together, the bars being fastened permanently to a bracket 16 secured to the manifold. The top bar 17 is a brass one and the under bar 18 is a steel one, such arrangement causing the valve 15 to move away from the seat under increasing temperature conditions and to move towards the seat as the temperature lowers. The valve and bars carrying the same are enclosed within a casing 19 suitably fastened to the intake manifold and having one end open as indicated at 20 to admit outside air. An adjusting screw 21 is carried by the casing and is adapted to engage with the upper bar 17, such adjusting screw being adapted to regulate the extreme open position of the valve. To the valve 15 I connect a rod 22 which passes downwardly centrally of the pipe 10 and is provided at its lower end with a plunger valve 23, the latter valve being slidably mounted in the lower end of the pipe 10 in a position normally beneath the lower side of the nipple 12.

According to this arrangement it will be apparent that any movement of the valve 15 causes a corresponding movement in the valve 23 and that should the valve 15 rise sufficiently high the valve 23 will open by moving inwardly a sufficient amount to permit cold air to pass through the lower end of the pipe 10 and into the pipe 13. The

pipe 13 leads to a valve casing 24 attached to the intake manifold 2 in a location above the throttle valve 5.

Within the casing I locate a barrel or cylinder 25, there being an annular chamber 26 reserved between the barrel and the wall of the casing. The ends of this annular chamber are closed and the barrel is provided with lengthwise extending V-shaped slots 27 having the small ends of the slots at the end next the intake manifold. An inlet passage 28 leads from the inner end of the barrel to an L-shaped pipe 29 entering the intake manifold and having the free end thereof turned upwardly and terminating in a perforated ball or mixer 30 positioned centrally of the manifold. A controlling valve 31 is slidably mounted in the barrel and the said valve is partly cylindrical and partly conical and the cone shaped end 32 extends towards the intake manifold and when said valve is moved to the right is adapted to close against the seat 33 and thereby close entrance to the passage 28. In connection with this valve 31 it is pointed out that as the said valve moves to the left within the barrel it gradually opens the slots 27 and by so doing permits a gradually increasing volume of air to pass from the chamber 26 to the passage 28, this by virtue of the V-shape of the slots. A valve stem 34 is connected to the valve 31 and passes outwardly through the end of the casing and is connected pivotally to an operating rod 35 which is pivotally attached to the throttle rod 7. According to this latter arrangement, as the throttle rod 7 is shifted by the automobile driver to open or close the throttle valve, the valve 31 is correspondingly opened and closed.

An adjusting screw 36 is screw threaded into the casing 24 and is adapted when screwed in to pass into the passage 28. This screw will decrease the area of the passage, depending on the amount that it is screwed in.

In the drawing I have shown the throttle valve in a partially open position and on this account the valve 31 is shown partially open.

When an engine with my appliance thereon is started the valves 15 and 23 are closed, although the valve 31 may be open, depending on the position of the throttle valve. The engine, accordingly, starts under ordinary conditions. As the engine gradually warms up, the exhaust manifold becomes warm, as does the interior of the casing 19. The valve 15 will accordingly gradually open, depending on the temperature condition in the casing. As the valve 15 opens, warm air is admitted to the pipe 10 and is heated in the pipe by the passing exhaust gases. From the pipe 10 the hot air is led through the pipe 13 to the pipe 29 and is thoroughly mixed with the upgoing firing

mixture as it escapes through the openings of the head 30. This hot air effectively pre-heats and vaporizes the firing mixture and thereby materially increases its efficiency in the engine cylinders. As the valve 15 produces a similar movement in the valve 23 one can, by properly positioning the valve 23 in respect to the nipple, have the temperature of the air passing through the pipe 13 controlled in accordance with the operating conditions of the engine and such control is entirely automatic.

For all normal running conditions of the engine the valve 15 is open and the valve 23 is closed, and by being closed I mean there is no cold air admitted to the pipe 13 through the lower end of the pipe 10. Should the engine, however, become abnormally hot the valve 15 will open to such an extent that cold air will be admitted through the lower end of the pipe 10 to the pipe 13 past the valve 23. In an overheated condition of the engine the valve 15 could be so far open that the valve 23 would close the pipe 10 above the nipple so that there would be no hot air whatever admitted to the pipe 13. I mention this latter feature to show more clearly the control which these two valves can have over the air passing through the pipe 13 and in this connection it is pointed out that the control is entirely thermostatic. The amount of air, however, finally reaching the intake manifold to be mixed with the firing mixture, is entirely controlled by the valve 31 which in turn operates in unison with the throttle valve.

What I claim as my invention is:

1. The combination with the intake and exhaust manifolds of an internal combustion engine, of a mixer contained within the intake manifold, a pipe passing through the exhaust manifold and having the ends thereof open and forming a heater, a pipe connecting the heater with the mixer and thermostatically controlled valves operating in tandem at the opposite ends of the heater and automatically controlling the admission of air to the heater.

2. The combination with the intake and exhaust manifolds of an internal combustion engine, of a mixer contained within the intake manifold, a pipe passing through the exhaust manifold and forming a heater, one end of the pipe forming an exterior valve seat and the other end being extended beyond the exhaust manifold to provide an inlet for exterior air, a pipe connecting the extended end of the former pipe with the mixer, a casing associated with the exhaust manifold and enclosing the valve seat, a thermostatically controlled valve mounted within the casing and adapted to seat on the valve seat and to admit a greater or less amount of air to the heater, depending on temperature conditions, a valve slidably

5 mounted in the lower end of the heater pipe and connected to the former valve to move therewith, said sliding valve controlling the admission of air through the lower end of the heater pipe.

10 3. The combination with the intake and exhaust manifolds, the throttle valve and throttle valve controlling rod of an internal combustion engine, of a mixer contained within the intake manifold above the throttle valve, an air pipe, a valve introduced between the air pipe and the mixer and controlling the amount of air admitted to the mixer from the air pipe, a connection between the valve and the throttle valve controlling rod whereby the movement of the valve is controlled by the throttle rod, an air heater associated with the exhaust manifold and communicating with the air pipe, 15 and thermostatically controlled air inlet valves associated with the heater and controlling the admission of hot and cold air to the heater.

20 4. In an internal combustion engine, auxiliary air supply means comprising a tube passing through the exhaust manifold, a delivery pipe leading from the tube and connected thereto at a point between one

25 end of the tube and the manifold, a valve slidably mounted in the tube and normally positioned between the delivery pipe and the adjacent end of the tube, a second valve normally closing the tube at the opposite end, a connection between said valves and a thermostat for operating the valves.

30 5. In an internal combustion engine, the provision of auxiliary air supply means comprising an air receiver, means for heating a portion of said receiver, a delivery pipe leading from the receiver, thermostatic 40 valve means controlling the passage of air through the receiver in such manner as to permit either hot or cold air to pass through the receiver to the delivery pipe dependent upon engine temperature, a valve casing 45 connected to the engine manifold and to the delivery pipe and a valve mounted in said casing to control passage of air between the delivery pipe and the manifold.

35 Signed at Winnipeg, this 7th day of June, 50
1923.

FREDERICK JAMES WEST.

In the presence of—

GERALD S. ROXBURGH,
MADELIENE B. KELLEHER.
